A. HUFFER.

COMBINATION OF STEAM AND WATER POWER.

No. 37,344.

Patented Jan. 6, 1863.

Minneses,
S. Breed
Daniel Breed

UNITED STATES PATENT OFFICE.

A BRAHAM HUFFER, OF HAGERSTOWN, MARYLAND.

IMPROVEMENT IN THE COMBINATION OF STEAM AND WATER POWER.

Specification forming part of Letters Patent No. 37,344, dated January 6, 1863.

To all whom it may concern:

Be it known that I, ABRAHAM HUFFER, of Hagerstown, in the county of Washington and State of Maryland, have invented a new and useful Improvement in Steam and Water Powers Combined; and I do hereby declare that the following is a full and exact description thereof, reference being had to the accompanying drawings, and to the letters of reference marked thereon.

In many parts of the country the streams are so low in summer that the water-powers dependent upon such streams are either compelled to rest or run only a part of the time. Often it is found advantageous to employ a steam-engine to temporarily replace these water-powers or to run in connection therewith while the water is low, the steam-power being put at rest, in order to save fuel and other expenses, as soon as the water rises in the stream. In such cases, and perhaps in some others, I believe it will prove economical to employ the exhaust-steam in raising water according to the well-known principles of hydraulics or the raising of water by the use of a vacuum and atmospheric pressure. Accordingly I have constructed and put into actual operation a machine which, raising its water by exhaust-steam, employs that water for turning a water-wheel.

The object of my invention is chiefly to utilize exhaust-steam from an engine necessarily employed in other work, and convert the same to an available power in driving machinery, thus saving expense.

My invention consists in the combination of a water-wheel or water-wheels with a steam-generator or steam-generators for the purpose of elevating water by means of the condensation of steam and atmospheric pressure, and then employing such water for operating the water wheel or wheels.

It will be necessary in carrying out my plan to employ two or more chambers to receive the exhaust-steam, so that one chamber may be receiving steam while the other is receiving and discharging water. I propose to have two dams and ponds or reservoirs of water, one being placed above the water-wheel and the other below it. When the water has been once used to turn the water-wheel, it flows into the lower pond or reservoir, from which it is brought back to the upper pond by the

use of the exhaust-steam to produce a vacuum in the chambers, and of atmospheric pressure to force up the water.

In the accompanying drawings I have represented a machine which illustrates my invention, but which will require considerable change of arrangement (though not in principle) for the most advantageous practical operation.

In these drawings, Figure 1 is a side elevation of my machine. Fig. 2 is a top view of the same.

In the drawings, Fig. 1, at A is seen a water-wheel, which may be of any construction and employed for any desired purpose. At B and C, Fig. 1, are represented two pans, which may be regarded as the two ponds or reservoirs of water employed in driving the water-wheel A. The water from the upper pan or pond, B, flows upon the water-wheel through the spout or flume D, thus giving motion to the wheel in the usual manner. As the water escapes from the wheel, it flows into the lower pan or reservoir, C, from which it may be brought back to the upper reservoir, as follows: The steam boiler or generator E may be employed to drive the steam piston or engine shown in the drawings. This engine may be of the usual construction, with the cylinder K, piston-rod I, and provided with wheel L, and any other desired arrangement for driving machinery. In the drawings a small alcohol-lamp, F, is placed under the boiler, instead of a furnace, which in a large machine or establishment may be of usual construction. The exhaust-steam from the cylinder K may be conducted through tubes O O' to the chambers N N', in order to expel the air from the latter. It is so arranged that one of these chambers is first filled with steam and then the other, so that one chamber is being filled with water while the other is being filled with steam. When the chamber N, for instance, is filled with steam, the flow of steam thereto is cut off, and the steam from the engine is then turned into the other chamber, N'. At the same moment a jet of water is let into chamber N, condensing the steam therein and forming a vacuum. Now the water from reservoir C rushes up the pipe h, filling the chamber N, as above described. Then the other chamber, N', is filled in turn, and the water from both chambers flows into the reser-

voir B, to be again employed in turning the water-wheel A.

In order to practically test my machine as above described, I have resorted to temporary arrangements, especially in the modes of working the valves; but, the principles being illustrated, the details may be varied at the pleasure of the mechanic when a full-sized machine is constructed. In the steam-pipes O and O', I have arranged valves and pistons R R', for cutting off the steam. As the chamber N is being filled with steam, the valve-rod R' is drawn back by means of lever S, the lower end of which works against a series of pins on the wheel U. When the chamber N is filled with steam, the lever S is released from the pins on wheel U by the revolution of the latter, and thus the valve closes by the action of the coiled spring T. At the next moment, the lever V strikes another pin on wheel U, and, being thus tripped, the upper end of this lever presses down the short arm W, rocking the shaft Y, and opening a valve, Z, admitting a jet of water into chamber N from the cistern a. This water condenses the steam in the chamber when water is forced from the reservoir C up the pipe h by atmospheric pressure suddenly filling the chamber N. Then the lever b is tripped by a pin on wheel U, thus opening the water-valve e, and also the air-valve d, and letting the water flow from the chamber while the same is being filled with air. These valves are hung by hinges, so that a slight pressure of the lever opens them. The air-valve d is closed by a spring, i, and the water-valve may be held in

like manner, though it is usually closed by atmospheric pressure. The other chamber, N', is filled and emptied in like manner. In this way the water is brought back from reservoir C into reservoir B, and may be used again and again for driving the water-wheel A. The boiler is provided with the usual safety-valve, j, held by a weight, H. This and other details may be varied at the pleasure of the mechanic without departing from my invention.

My invention may be advantageous in connection with simple reservoirs without any natural stream of water and mill-fall. On a large scale it may be found necessary to employ more than two chambers. If desired, the steam may be sent direct from the boiler E through part of pipes O O' without going to the steam-cylinder or being used for driving machinery. In that case stop-cocks will be necessary to direct the steam away from the steam-cylinder.

Having thus fully described my invention, what I claim, and desire to secure by Letters Patent of the United States, is—

The combination of a steam-generator or steam-generators with a water-wheel or water-wheels and chambers, or a chamber, for elevating water by atmospheric pressure and driving a water wheel or wheels, substantially in the manner and for the purposes set forth.

ABRAHAM HUFFER.
